UNITED STATES PATENT OFFICE

2,578,046

VEHICLE DETECTING DEVICE

Benjamin Cooper, New York, and Stanley A. Kroll, Brooklyn, N. Y.; said Kroll assignor to said Cooper

Application July 21, 1950, Serial No. 175,133

9 Claims. (Cl. 177—311)

1

This invention relates to vehicle detecting devices and is particularly directed to a treadle actuated system for detecting the presence of a vehicle in a berth or dock.

In applicants' co-pending patent application filed July 21, 1950, Serial No. 175,134, titled: Vehicle Assigning, Detecting and Dispatching Systems, there is described and claimed a system for assigning, detecting and dispatching busses at a multi-berth bus terminal. Though the present invention is especially adaptable for use in detecting the presence of a vehicle in vehicle berths equipped with said dispatching systems, other uses will readily present themselves to those skilled in the art; for instance, another use could be to automatically open a garage door upon vehicle passage over the treadle in the direction of entrance into the garage, and to subsequently close the door upon the vehicle leaving the garage and transversing said treadle in the opposite direction.

It is one object of this invention to provide a treadle actuated vehicle detecting system of the character described that is responsive to the rolling action of vehicle wheels passing over the treadle and at the same time is not responsive to the actions of pedestrians in walking or jumping on the treadle.

It is another object of this invention to provide a system of the character described that becomes actuated upon the passage of one wheel, or pairs of wheels, or the first of any number of wheels, or pairs of wheels, over the treadle in one direction, and subsequently becomes deactuated upon the passage of one wheel, or pairs of wheels, or the first one of any number of wheels, or pairs of wheels, over the treadle in the opposite direction.

It is another object of this invention to provide a system of the character described that will not remain actuated if a vehicle wheels, after mounting the treadle, rolls back and forth while on the treadle, subsequently backing off the treadle.

Other objects of this invention will in part be obvious and in part herein below pointed out.

The invention, accordingly, consists in the features of construction, combination of elements and arrangement of parts which will be exemplified in the construction herein below described and of which the scope of application will be indicated in the appended claims.

In the accompanying drawings, in which one of the various possible embodiments of this invention is illustrated:

Figure 1 is a schematic diagram of the electrical circuit, and Figure 2 is a partial perspective

2

drawing illustrating the typical location of treadles in berths of a multi-berth vehicle terminal.

Referring now to Figure 1, 10 represents a treadle comprising an elongated flexible casing 11 in which are fixed a first pair of switch contact strips 12 and 12a, and a second pair of switch contact strips 13 and 13a, longitudinally disposed in said casing and spaced apart, one pair from the other, about three inches. Said treadle is adapted to be placed in a road-bed, transversally of the direction of vehicle passage, so as to be actuated by the passing of wheels over the treadle.

Upon the passage of a vehicle over the treadle 15 in the direction indicated by the arrow, the switch 12, 12a will first be closed by the pressure of the vehicle rolling on the treadle; then, as the wheels advance, the switches 12, 12a and 13, 13a will be closed concurrently; then, as the wheels 20 continue to advance the switch 12, 12a opens while switch 13, 13a remains closed; and finally as the axle passes over the treadle, the switch 13, 13a will open. The opposite sequence of switch operation takes place, of course, upon the wheels 25 of a vehicle moving over the treadle in the opposite direction. Such a treadle as above described is illustrated and described in detail in U. S. Patent No. 2,251,351, issued August 5, 1941, titled: Treadle Process.

30 Included in the electrical circuit are auxiliary relays 14, 15, 16 and 17, and control relay 18. Each of said relays is furnished, respectively, with energizing coils 19, 20, 21, 22 and 23, each of which has one terminal connected to the negative 35 terminal of a direct current source.

Relay 14 has associated with it a movable contact arm 14b, normally in contact with fixed contact arm 14a, but adapted to be moved from contact therewith and into contact with contact arm 14c upon the energization of said relay. Relay 15 has associated with it a movable contact arm 15b, normally in contact with fixed contact arm 15a, but adapted to be moved from contact therewith and into contact with contact arm 15c upon 45 the energization of said relay.

Relay 16 is provided with a normally closed switch 16a, 16b, adapted to be opened when said relay is energized.

Relay 17 is provided with a normally open switch 17a, 17b, adapted to be closed when said relay is energized.

Relay 18 is provided with two pairs of switches, 18a, 18b, and 18c, 18d, each normally open but adapted to be closed when said relay is energized.

55 The switch contact strip 12a and 13a are each

connected to the positive terminal of the direct current source. The switch contact strip 12 is connected as by wire 24 to the movable contact arm 14a associated with relay 14. Switch contact strip 13 is connected as by wire 25 to movable contact arm 15b associated with relay 15.

Fixed contact arm 14c associated with relay 14 is connected as by wire 26 to the remaining terminal of energizing coil 20 associated with relay 15. Fixed contact arm 15a associated with relay 15 is connected as by wire 27 to the remaining terminal of energizing coil 19 associated with relay 14.

Fixed contact arm 14c is connected as by wire 28 to the remaining terminal of energizing coil 21 associated with relay 16. Fixed contact arm 15c is connected as by wire 29 to the remaining terminal of energizing coil 22 associated with relay 17.

Fixed contact arm 16a associated with relay 16, movable contact arm 17a associated with relay 17, and fixed contact arm 18d associated with relay 18 are each connected to the positive terminal of the direct current source.

Movable contact arm 16b is connected as by wire 30 to movable contact arm 18a associated with relay 18. Fixed contact arm 17b is connected as by wire 31 to the remaining terminal of energizing coil 23 associated with relay 18, and also, as by wires 31 and 32, to fixed contact arm 18b associated with said relay.

Movable contact arm 18c associated with relay 18 is connected as by wire 33 to one energizing terminal of indicator lamp 34, the other energizing terminal of said lamp being connected to the negative terminal of the direct current source.

Referring to Figure 2 it is seen how the treadle 10 is placed in the floor of the vehicle berth 35 so as to be traversed by the front wheels at least when a vehicle enters the berth in the direction indicated by the arrow.

Considering now the operation of the system, assume that a vehicle is entering the berth and passing over the treadle. The treadle switch 12, 12a will just be closed, completing a circuit to energize relay 15, said circuit being from direct current plus, through now closed switch 12, 12a, wire 24, normally closed switch 14a, 14b, wire 26, through energizing coil 20 to direct current minus. The energization of said relay will open switch 15a, 15b and close switch 15b, 15c. As the wheels of the vehicle advance further so as to close concurrently the treadle switches 12, 12a and 13, 13a, an energizing circuit will be completed to relay 17, said circuit being from direct current plus, through now closed switch 13, 13a, wire 25, now closed switch 15b, 15c, wire 29, through energizing coil 22 to direct current minus. The energization of relay 17 will in turn effect the completion of a circuit to energize control relay 18, said circuit being from direct current plus, through now closed switch 17a, 17b, wire 31, through energizing coil 23 associated with relay 18 to direct current minus. The energization of relay 18 will cause the completion of a secondary energizing circuit for itself, said circuit being from direct current plus, through normally closed switch 18a, 18b, wire 30, now closed switch 18a, 18b, wires 32 and 34, through energizing coil 23 of said relay.

The actuation of relay 18 closes switch 18c, 18d, completing an energizing circuit to lamp 34 to indicate the passage of a vehicle wheel over the treadle.

As the wheel continues to move over the treadle, the switch 12, 12a opens next, opening the above

detailed energization circuit to relay 15. The energization of control relay 18 will not be interrupted, however, because of the above detailed secondary energization circuit which remains closed-circuited. It should be noted here that although upon the de-energization of relay 15, relay 14 becomes energized, the circuit being from direct current plus, through now closed switch 13, 13a, wire 25, normally closed switch 15a, 15b, wire 27, through energization coil 19 of relay 14 to direct current minus, relay 16 remains de-energized, since treadle switch 12, 12a, in its energization circuit is now open.

As the wheels roll off the treadle, opening switch 13, 13a, the above detailed energization circuit to relay 14 is opened, de-energizing it. Relay 18 will remain energized, however, its secondary energization circuit remaining uninterrupted.

Assume now that a second pair of wheels pass over the treadle upon a vehicle entering the berth. This might happen, for instance, in the case of a very short car being docked in a berth designed primarily for large vehicles. As detailed above, relay 15 will first become energized upon the closure of treadle switch 12, 12a. Upon the concurrent closure of switches 12, 12a and 13, 13a, relay 17 will become energized, as above. However, since control relay 18 is already energized through its secondary energization circuit, the energization of relay 17 has no effect. As the wheels continue over the treadle circuit operation will be the same as detailed above for the passage of the first pair of wheels.

Consider now the operation of the system when a vehicle backs out of the berth. Treadle switch 13, 13a will first be closed, completing a circuit to energize relay 14, said circuit being from direct current plus, through closed switch 13, 13a, wire 25, normally closed switch 15a, 15b, wire 27, through energizing coil 19 associated with relay 14 to direct current minus. Upon the subsequent closure of the treadle switch 12, 12a as the wheels move backwards across the treadle a circuit is completed to energize relay 16, said circuit being from direct current plus, through closed treadle switch 12, 12a, wire 24, now closed switch 14b, 14c, wire 28, through energizing coil 21 associated with relay 16 to direct current minus. The energization of relay 16 will be in turn opening the secondary energizing circuit through switch 16a, 16b to control relay 18, de-actuating it. The de-actuation of the control relay will open switch 18c, 18d, de-energizing indicator lamp 34 and thereby signalling that a vehicle is leaving the berth.

As the wheels continue to move over the treadle the switch 13, 13a will next open, open-circuiting to above detailed energization circuit to relay 14. At the same time relay 15 will become energized through the circuit from direct current plus, through closed switch 12, 12a, wire 24, normally open switch 14a, 14b, wire 26, through energization coil 20 associated with relay 15 to direct current minus. However, since the treadle switch 13, 13a is now open, there can be no completed energization circuit to control relay 18. As the wheels continue over the treadle the switch 12, 12a will finally be opened, effecting the de-energization of relay 15.

It is evident from the foregoing description of circuit operation that the passage of a second pair of wheels, or any number of sets of wheels, backwardly over the treadle cannot energize control relay 18, since no circuit will be completed

to relay 17 as is necessary to initially energize control relay 18.

It will thus be evident that there is provided a device in which the several objects of this invention are achieved, and which is well adapted to meet the various conditions of practical use.

Having thus described our invention, we claim as new and desire to secure by Letters Patent:

1. In combination with a treadle, comprising a set of two switches adapted to be closed in sequential order by the wheels of a vehicle rolling thereover, an electrically operated indicator means, a circuit connecting said switches with said indicator means, including means, operable upon actuation and de-actuation of said switches sequentially and concurrently in one direction, to energize said indicator means and retain the same in energized condition, and means operable upon actuation and de-actuation of said switches sequentially and concurrently in the opposite direction, to de-energize said energized indicator means.

2. In combination with a treadle, comprising a set of two switches adapted to be closed in sequential order by the wheels of a vehicle rolling thereover, an electrically operated indicator means, a circuit connecting said switches with said indicator means, including means, operable upon actuation and de-actuation of said switches sequentially and concurrently in one direction, to energize said indicator means and retain the same in energized condition, and means operable upon actuation and de-actuation of said switches sequentially and concurrently in the opposite direction, to de-energize said energized indicator means, said circuit further including means to retain said energized indicator means in energized condition upon actuating said switches in the first direction subsequent to the first actuation of said switches in said first direction and before actuating said switches in said opposite direction.

3. In combination with a treadle, comprising a set of two switches adapted to be closed in sequential order by the wheels of a vehicle rolling thereover, an electrically operated indicator means, a circuit connecting said switches with said indicator means, including means, operable upon actuation and de-actuation of said switches sequentially and concurrently in one direction, to energize said indicator means and retain the same in energized condition, and means operable upon actuation and de-actuation of said switches sequentially and concurrently in the opposite direction, to de-energize said energized indicator means, and means to retain said indicator means in de-energized condition upon actuation of said switches in the opposite direction at any time while said indicator means is in de-energized condition.

4. In combination with a treadle, comprising a set of two switches adapted to be closed in sequential order by the wheels of a vehicle rolling thereover, an electrically operated indicator means, a circuit connecting said switches with said indicator means, including means, operable upon actuation and de-actuation of said switches sequentially and concurrently in one direction, to energize said indicator means and retain the same in energized condition, and means operable upon actuation and de-actuation of said switches sequentially and concurrently in the opposite direction, to de-energize said energized indicator means, said circuit further including means to retain said energized indicator means in ener-

gized condition upon actuating said switches in the first direction subsequent to the first actuation of said switches in said first direction and before actuating said switches in said opposite direction, and means to retain said indicator means in de-energized condition upon actuation of said switches in the opposite direction at any time while said indicator means is in deenergized condition.

5. In combination with a treadle, comprising a set of two switches adapted to be closed in sequential order by the wheels of a vehicle rolling thereover, an electrically operated indicator means, a circuit connecting said switches with said indicator means, including means, operable upon actuation and de-actuation of said switches sequentially and concurrently in one direction, to energize said indicator means and retain the same in energized condition, and means operable upon actuation and de-actuation of said switches sequentially and concurrently in the opposite direction, to de-energize said energized indicator means, said switches being parallel and spaced apart not more than three inches.

25 6. A treadle comprising first and second treadle switches over which the wheels of a vehicle may roll, a first treadle switch relay, means to energize said first treadle switch relay upon closing the first treadle switch, an auxiliary control relay, means to energize the auxiliary control relay upon closing the second treadle switch while the first treadle switch remains closed, a control relay, means to energize the control relay upon the energization of the auxiliary control relay, an electrical indicator, means to energize said indicator upon the energization of said control relay, a holding circuit for holding the control relay in energized condition, operated by the energization of said control relay, upon opening the first 30 treadle switch after said control relay is energized, thereby de-energizing the first treadle switch relay and also the auxiliary control relay, and means to retain the control relay and hence the indicator in energized condition upon subsequently opening the second treadle switch.

7. A treadle comprising first and second treadle switches over which the wheels of a vehicle may roll, a first treadle switch relay, means to energize said first treadle switch relay upon closing the first treadle switch, an auxiliary control relay, means to energize the auxiliary control relay upon closing the second treadle switch while the first treadle switch remains closed, a control relay, means to energize the control relay upon the energization of the auxiliary control relay, an electrical indicator, means to energize said indicator upon the energization of said control relay, a holding circuit for holding the control relay in energized condition, operated by the energization of said control relay, upon opening the first 45 treadle switch after said control relay is energized, thereby de-energizing the first treadle switch relay and also the auxilliary control relay, means to retain the control relay and hence the indicator in energized condition upon subsequently opening the second treadle switch.

50 8. A treadle comprising first and second treadle switches over which the wheels of a vehicle may roll, a first treadle switch relay, means to energize said first treadle switch, an auxiliary control relay, means to energize the auxiliary control relay upon closing the second treadle switch while the first treadle switch remains closed, a control relay, means to energize the control relay upon the energization of the auxiliary control relay, an electrical indicator, means to energize said indicator upon the energization of said control relay, a holding circuit for holding the control relay in energized condition, operated by the energization of said control relay, upon opening the first 55 treadle switch after said control relay is energized, thereby de-energizing the first treadle switch relay and also the auxilliary control relay, means to retain the control relay and hence the indicator in energized condition upon subsequently opening the second treadle switch, a second treadle switch relay, means to energize said second treadle switch relay upon subsequently closing the second treadle switch, a holding relay, 60 means to energize the holding relay upon subsequently closing the first treadle switch while the second treadle switch is closed, said holding relay, when energized, being adapted to open the holding circuit for the control relay to de-energize the second treadle switch relay upon sub-

sequently opening the second treadle switch while the first treadle switch remains closed.

8. In combination with a treadle, comprising a set of two switches adapted to be closed in sequential order by the wheels of a vehicle rolling thereover, an electrically operated device, a circuit connecting said switches with said device, including means, operable upon actuation and de-actuation of said switches sequentially and concurrently in one direction, to energize said device and retain the same in energized condition, and means operable upon actuation and de-actuation of said switches sequentially and concurrently, in the opposite direction, to de-energize said energized device.

9. In combination with a treadle, comprising a set of two switches adapted to be closed in sequential order by the wheels of a vehicle rolling thereover, an electrically operated device, a circuit connecting said switches with said device, including means, operable upon actuation and de-actuation of said switches sequentially and con-

currently in one direction, to energize said device and retain the same in energized condition, and means operable upon actuation and de-actuation of said switches sequentially and concurrently in the opposite direction, to de-energize said energized device, said circuit further including means to retain said energized device in energized condition upon actuating said switches in the first direction subsequent to the first actuation of said switches in said first direction and before actuating said switches in said opposite direction.
